PROPELLER GUARD

John R. Benson, East St. Louis, Ill.

Application January 17, 1938, Serial No. 185,391

4 Claims. (Cl. 115—42)

This invention relates to propeller guards, and has special reference to guards for propellers of outboard motors or the like.

An object of the invention is to provide an improved guard for use in protecting propellers from injury by any submerged materials or substance, such as rocks and stones, or logs and trees, and also to prevent interference with lines used in trolling or other fishing activities.

10 Another object of the invention is to provide a guard for outboard motor propellers and the like that will prevent vegetation, such as grasses and weeds and the like, from becoming entangled with the propeller and causing delays, and perhaps 15 damage and injury to the propellers.

Other objects will appear from the following description, reference being made to the annexed drawing, in which—

Fig. 1 is a rear elevation of a propeller having 20 my invention mounted to guard and protect the same.

Fig. 2 is a side elevation of the propeller protected by my improved guard.

Fig. 3 is a front elevation.

25 For convenience of illustration, my invention is shown applied as a guard for the propeller of an outboard motor of known construction and including a tube 1 for the propeller drive shaft, an exhaust tube 2 and an oil line tube 3. A flange 30 or plate 4 is attached to the lower ends of said tubes and holds them in rigid relationship. The propeller 5 is driven by gearing within a housing 6 operated by the usual propeller drive shaft enclosed within the tube 1. The skeg 7 curves 35 downwardly and rearwardly from integral connection with the housing 6 and terminates substantially below the lowest position of the propeller 5, as is well known.

40 My invention comprises a metallic frame including an approximately circular member 8 bent to provide abutting portions 9 adapted to abut against the side edges of the flange 4, and overlapping end portions 10 adapted to seat upon the flange 4; and a frame member comprising a 45 curved portion 11 having its lower and rear end attached to the frame member 8, a portion 12 seating against the front of the housing 6, and a rebent portion 13 embracing the front portion of the flange 4. The curved portion 11 is formed 50 with a slot 14 through which the skeg 7 extends, the rear edge of said skeg 7 preferably engaging one end of the slot.

55 Detachable fasteners 15 passing through the ends 10 and the upper end of the rebent portion 13, in cooperation with the engagement between

the skeg 7 and the frame member 11, hold the frame in rigid position with respect to the propeller 5 and the housing 6. The frame member 8 extends rearwardly beyond the propeller 5 and functions to prevent trolling lines, or vegetation 5 and the like, from becoming entangled with the propeller.

A section of screen 16 or equivalent material is placed on the inside of the frame comprising the member 8 and the cooperating member 11, 10 12, and is held clamped against the front end of the housing 6. This section of screen material or the like is welded or otherwise attached to the frame members and is slotted or pressed to permit the skeg 7 to extend through the slot 14 to 15 provide an interlocking connection.

This device may be made and assembled in connection with the propeller devices of familiar types of outboard motors and, in use, has been found eminently satisfactory in protecting the 20 propeller and also in preventing trolling lines and the like from becoming entangled with and severed by the propeller. The device may be manufactured and assembled economically and attains all of its intended objects and purposes efficiently 25 25 and satisfactorily. The invention may be varied within the scope of equivalent limits without departure from the nature and principle thereof.

I claim:—

1. In an outboard-motor having a submersible 30 propeller, means for supporting the propeller, and a rigid element in connection with said means above the propeller; an annular frame member engaging the rear of said means, a frame element 35 engaging the front of said means and attached to said frame member below the propeller, detachable devices holding said frame member and said element in engagement with said means, and a screen device enclosing the sides and front of 40 said propeller and attached to said frame member and said frame element.

2. In an outboard-motor boat propeller having a housing for supporting the propeller, mechanism for rotating the propeller, a skeg rigid with the housing and extending downwardly to a plane 45 below the propeller, and an element rigid with the housing above the propeller; a frame member engaging said element and extending rearwardly beyond and downwardly below the propeller, a frame element having its upper end engaging said 50 first named element and its lower end attached to said frame member below the propeller and having a slot therein through which said skeg extends and holds said element rigid, and a screen 55 enclosing the front and sides of said housing

and said propeller and attached to said frame member and said element, preventing vegetation and troll fishing lines from being caught by the propeller and leaving said propeller free to rotate.

5   3. In an outboard motor submersible propeller device including a housing for enclosing mechanism to rotate a propeller, a propeller supported at the rear of said housing, and a flange rigid with said housing above said propeller; a frame 10 member extending rearwardly beyond and downwardly below said propeller and having its upper portion engaging said flange, a frame element having a slot therein through which a portion of said housing extends and being attached at its 15 lower end to said frame member and at its upper end to said flange, means detachably holding said frame member and said element in engagement with said flange, and a screen device enclosing the front and sides of said housing and said propeller and extending between said frame element 20 and said housing and being attached to said frame member and said element.

4. In outboard submersible propeller mechanism including a support, a housing attached to and extending downwardly from said support, a flange extending rearwardly and laterally beyond said housing, a propeller rotatively supported at 5 the rear of said housing, and a rearwardly curved part extending downwardly from said housing below said propeller; an open and unobstructed frame engaging said flange and being of larger diameter than the diameter of said propeller and 10 extending rearwardly beyond said propeller, a connection having its upper end engaging the front of said flange and its lower end extending rearwardly and rigidly engaging said housing and also being rigidly attached to said frame, means 15 detachably holding said frame member and said element in engagement with said flange, and a screen section rigidly attached to said frame and forming a screen enclosure within which said propeller rotates freely and which is open toward 20 the rear.

JOHN R. BENSON.
